JEAN F. WEBB, JR., OF NEW YORK, N. Y., ASSIGNOR TO THE INTERNATIONAL SIGNAL CO., INCORPORATED, OF NEW YORK, N. Y.

PLUNGER DEVICE FOR TRAIN-STOPPING APPARATUS.

1,199,643.

Specification of Letters Patent. Patented Sept. 26, 1916.

Application filed April 1, 1916. Serial No. 88,295.

To all whom it may concern:

Be it known that I, JEAN F. WEBB, Jr., residing at New York, in the county of New York and State of New York, have invented 5 certain new and useful Improvements in Plunger Devices for Train-Stopping Apparatus, of which the following is a specification.

My present invention is an improved 10 plunger device especially designed and adapted for use in connection with such train stopping apparatus as, for instance, are disclosed in the patent to Jean F. Webb, Jr., issued January 19, 1915, #1,125,418, the 15 patent issued to Jean F. Webb, Jr., #1,125,419, January 19, 1915 and the patent issued to Jean F. Webb, Sr. and Jean F. Webb, Jr., February 8, 1816, #1,170,789. In train stopping mechanism of these general types 20 a reciprocating plunger is provided for actuating the valves or other mechanisms that release the air to set the brakes and bring the train to a stop when the plunger is engaged, under certain conditions, by the 25 track ramp or other similar plunger raising device.

The present invention has for its object to provide a plunger device of general application that is not only adapted for use in connection with the mechanism disclosed in the 30 aforesaid patents but may be employed in connection with other train stopping mechanism in which a reciprocating part is employed for setting or operating purposes 35 and in the present application I make no claim to the construction of the mechanism *per se*, operated by the reciprocations of the plunger as such mechanisms form the subject-matter of the patents aforesaid.

40 The present invention especially has for its object to provide a plunger device in which provision is made for self-protection in such way that upon breakage of the plunger device, the air will be released to 45 act upon the brakes (through connection with the train pipe or with any other mechanism by which the release may be accomplished) and the brakes set until the damaged part can be repaired.

50 In the present invention provision is made for reducing the expense of manufacture to the minimum by reason of the fact that the plunger is made in two parts, one part of

which can be made of hard material, such as steel, and the other part of softer material, such as gray cast iron, or the like, the softer part being constructed with a weakened area that is designed to have sufficient strength, under all normal conditions, to resist breakage but in which, when a relatively 55 fixed obstruction is met, the force of impact between which and the plunger device is applied substantially normal to the reciprocatory axis of the plunger, the breakage will occur always at the same location namely, 60 the weakened area, so that in order to repair the plunger it is only necessary to remove a portion of the same, the construction being such that the removal of the broken part can be effected without disturbing the location of the plunger proper or any connection between it and the train stopping mechanism. 65

In its more detail nature, the invention includes certain novel features of construction, combination and arrangement of parts, all of which will be first fully described, then be specifically pointed out in the appended claims, and illustrated in the accompanying drawing, in which:— 70

Figure 1 is a central vertical longitudinal section illustrating the invention in the normal position of the parts. Fig. 2 is a cross section on the line 2—2 of Fig. 1. Fig. 3 is a plan view on the line 3—3 of Fig. 1, 85 the nipple being removed.

In the drawing, in which like letters and numerals of reference indicate like parts in all of the figures, 1 represents the relatively fixed support which has a guideway 2 bored 90 at 3 to receive the cylindrical plunger 10, the plunger 10 including the stem 8 which projects upwardly through the guideway 2 and has flat sides 9 to engage the flat portion 7 of the bore of the cap 4, the cap 4 being 95 provided with ears 5 through which cap screws 6 are passed to secure the cap 4 to the support 1. By reason of the flat faces 7 and 9, a turning of the plunger in the guideway 2 is prevented. 100

The plunger end 10 preferably projects below the guide 2 and extends into the guide 2 under all conditions. The plunger is bored at 13 for the passage of the bolts 14 whose heads 15 are held from turning by 105 engaging the flat sides 9 of the stem 8 of

the plunger and the bolts are held down by a washer 16 against which the buffer spring 17 presses, the springs 17 being located in the guide 2 around the stem 8 and also engaging the cap 4.

27 is a collar secured on the upper end of the stem 8 to limit the downward movement of the same and 26 is the nipple by means of which the air connection with the 10 air brake system is had to lead air under train pipe pressure into the bore 11 of the plunger proper.

The plunger proper is provided with a ground seat 12 into which the ground nipple 15 19 of the shoe body portion 18 fits, the shoe body portion 18 being, as it were, a continuation of the plunger proper 10 and is secured to the same by the bolts 14 which pass through the bores 20 of the body portion 18, nuts 21 and pins 22 being provided 20 on the bolts 14 for the usual purposes.

The plunger proper 10 is preferably constructed of hard metal, such as steel, and is designed to be a permanent structure, while 25 the shoe which consists of the body portion 18, the neck 24 and the foot 23, is preferably constructed of a softer material, the construction being such that the neck 24 provides a weakened area so designed, however, 30 to withstand all normal stresses encountered in practice, particularly those applied directly upward or at an inclination to the axes of reciprocation. The neck 24, however, is so designed if a relatively fixed construction 35 B is encountered, the impacting stresses resulting being applied in a relatively normal direction to the axes of reciprocation of the plunger, the neck 24 will break, thus releasing the train pipe air 40 through the passage 11 to the blind bore 25 (which is opened by the breakage) and setting the brakes on the train or operating the brake setting mechanism that may be provided for the purpose.

45 Common strains are applied by contact with the ramp A and do not affect the structure of the neck 24.

By making the plunger of two parts, one 50 of which is readily removed from the plunger proper, it will be seen that in order to repair the breakage, it will only be necessary for the engineer to unscrew the nuts 21, the bolts 14 being held from turning and from longitudinal movement by the heads 55 15 engaging the flat faces 9 and being pressed by the spring pressed washer 16. Having removed the nuts 21, the body 18 of the shoe can be drawn out and removed and a new shoe can be quickly substituted 60 for the same.

As the plunger usually requires accurate machining to operate properly in the guide 2 and under practical conditions, were it made in one piece and of the same hardness, 65 a breakage would likely occur at almost any

location, which would make it an expensive matter to remove the entire plunger from the apparatus for purposes of repair.

I am aware that heretofore pivoted contact arms have been provided with air passages designed to release train pipe air when the parts become worn or broken in use, but in the construction referred to (see patent to Phillip #827,940, issued Aug. 7, 1906) in order to replace the broken member F' of such patent, it is necessary to remove the entire structure from the apparatus and replace the entire member. This is a long and tedious operation, and furthermore breakage of the member F' is liable to occur 70 at any part of the device, no provision being made for compelling the breakage to occur always at the same location, as in my invention. I am also aware that heretofore a reciprocating plunger device has been provided with a fragile capsule designed to be broken each time the same encounters an obstruction. This, however, is an objectionable feature, for the reason that it requires the engineer to replace the destructive cap 80 every time a track obstacle is encountered, and such device could not be employed in train stopping apparatus of the type disclosed in my former patents referred to, as the delicate capsule (usually made of glass 85 or very thin metal) is not susceptible of 90 withstanding strains and stresses of an obstruction in any direction and would be substantially inoperative if made strong enough to withstand the pressures required to raise 95 the plunger if used in connection with my train stopping apparatus or others of the same type above referred to. The destructible capsule idea is disclosed, for example, 100 in the patent to Barbarie #825,289, issued July 10, 1906. My invention, however, differs from the devices of the Phillip and Barbarie patents in that the parts are 105 designed not to break under all ordinary conditions met with in practice and be of such 110 strength as to withstand the normal stresses and strains to raise the plunger against the action of the strong buffer spring to operate the mechanism with which the plunger, in 115 practice, is usually connected, and so designed, however, as to compel breakage to occur always at one location in the removable part when abnormal strains in a direction normal to the axis of reciprocation are 120 encountered.

Having thus described my invention, what I claim and desire to secure by Letters Patent is:

1. A plunger device for train stopping apparatus comprising a relatively fixed support having a guideway, a plunger reciprocable in said guideway, means for depressing said plunger, a shoe on the bottom of said plunger, said shoe having a weakened neck, said shoe having a blind bore and said 125 130

plunger having a bore registering with said blind bore and adapted for connection with the train pipe of an air brake system.

2. A plunger device comprising a supporting guideway, a plunger reciprocable in the same, said plunger having a bore through the same; a shoe comprising a foot portion, a body portion and a neck, said shoe having a blind bore extending through the body portion and the neck, and devices for detachably securing the body portion of the shoe to the plunger with the bores in register.

3. A plunger device comprising a supporting guideway, a plunger reciprocable in the same, said plunger having a bore through the same; a shoe comprising a foot portion, a body portion and a neck, said shoe having a blind bore extending through the body portion and the neck, devices for detachably securing the body portion of the shoe to the plunger with the bores in register, means for continuously applying pressure to said plunger in one direction, said plunger adapted to yield when other pressure is applied to the shoe in the opposite direction, said neck being adapted to resist normal diagonal strains in passing over track ramps and obstructions but designed to break when a fixed obstruction is encountered, the contact stresses of which are substantially normal to the axis of reciprocation of the plunger.

4. In a plunger device, a rigid support having a guideway, a plunger comprising a body bar longitudinally reciprocable in said guideway, a spring for holding said plunger bar down and a separate shoe extension member detachably secured to said plunger bar whereby the same may be removed and replaced at will without disturbing the position of the plunger bar in said guideway.

5. In a plunger device, a rigid support having a guideway, a plunger comprising a body bar longitudinally reciprocable in said guideway, a spring for holding said plunger bar down and a separate shoe extension member detachably secured to said plunger bar whereby the same may be removed and replaced at will without disturbing the position of the plunger bar in said guideway.

sition of the plunger bar in said guideway, said plunger bar and said shoe extension having a blind bore connectible to the train pipe of an air brake system.

6. In a plunger device, a rigid support having a guideway, a plunger comprising a body bar longitudinally reciprocable in said guideway, a spring for holding said plunger bar down and a separate shoe extension member detachably secured to said plunger whereby the same may be removed and replaced at will without disturbing the position of the plunger bar in said guideway, said plunger bar and said shoe extension having a blind bore connectible to the train pipe of an air brake system, and said shoe extension having a foot, a body part and a connecting neck between said parts, said shoe parts being constructed to withstand stresses in the direction of the length of the plunger bar, and diagonally thereto, said neck being constructed to break when abnormal strains only are applied in a direction substantially normal to the direction of reciprocation of the plunger.

7. A plunger device which comprises a relatively fixed support having a guideway, a plunger member reciprocable in said guideway and including a body portion and a stem, a spring in said guideway for forcing said plunger downwardly, means for limiting the downward movement of said plunger in said guideway to continuously cause said guideway to inclose said plunger forcing means, bolts carried by said plunger and projecting below the guideway, said plunger having a bar terminating in a seat, a shoe comprising a body portion having a nipple to fit in said seat and bore to receive said bolts, nuts on said bolts for securing said shoe body to said plunger member, said shoe including a neck pendent from said shoe body and a foot portion connected to said shoe body by said neck, said shoe having a blind bore registering with the bore of said plunger member all being arranged substantially as shown and for the purposes described.
